UNITED STATES PATENT OFFICE.

SAMUEL J. WALASCHEK, OF NEW YORK, N. Y.

CLOTHESLINE CONNECTION.

Application filed April 9, 1925. Serial No. 21,857

To all whom it may concern:

Be it known that I, SAMUEL J. WALASCHEK, a citizen of the United States, residing at New York, in the county of Bronx 5 and State of New York, have invented certain new and useful Improvements in Clothesline Connections, of which the following is a specification.

The present invention appertains to a device for holding the ends of clothes lines or the like together, and has for its principal object to provide an efficient and effective device of this nature, which is useful in replacing the lines of the endless clothes 15 line and pulley structure used in tenement and apartment houses.

It is desirable, from time to time, to replace the clothes line, in order that it may be washed, and if the ends are tied together, it is often very difficult not only to untie the knot, but to thread a new clothes 20 line through the pulley.

It is the aim of the present device to provide a structure which will efficiently hold 25 the ends of the clothes line together, and which will aid in replacing the clothes line.

Another important object of the invention is to provide a connection of this nature, which will easily pass over the wheels 30 of the pulley structure.

Another important object of the invention is to provide a connection of this nature, which is flexible, strong, durable, easy to attach and detach, thoroughly reliable, inexpensive to manufacture, and otherwise well adapted for the purpose for which it 35 is designed.

With the above and numerous other objects in view, as will appear as the description proceeds, the invention resides in certain novel features of construction, and in the combination and arrangement of parts as will be hereinafter more fully described and claimed.

In the drawing:

Figure 1 is an elevation, showing an endless clothes line structure, with my improved device associated therewith.

Figure 2 is an enlarged detail view of the device, showing a portion in section,

Figure 3 is a detail perspective view of one of the engaging clamps, and

Figure 4 is a detail perspective view of a modification of one of the engaging clamps.

Referring to the drawing in detail, it

will be seen that A designates the post of a back porch, on which is supported a pulley structure B in the usual manner. C designates a pole some distance from the back porch, and supporting in the usual manner 60 a pulley structure D. A clothes line E is trained over the pulley structures C and D and the ends thereof are held together by my improved connection, indicated generally by the letter F.

Referring particularly to Figures 2 and 3, the specific construction of this connection F will be more clearly understood. The numeral 5 designates a chain section, including a plurality of connected links, 70 and a plurality of anti-friction spherical members 6, one on each link of the chain section. Cylinders 7 have their closed ends 8 attached to the end links. The open ends of the cylinder 7 are threaded, as at 9, for the reception of cylindrical caps 10, the outer surfaces of which are milled, and the ends of which are provided with restricted openings formed by the inturned annular flanges 11. A U-shaped resilient clamp member 12, having its terminals inturned to form blades 13 is engaged with each end of the clothes line, as shown in Figure 2, the blades 13 biting into the line. After these clamp members 12 have been engaged 80 over the ends of the clothes line, the cylinders 7 are passed over the clamp members, thus retaining the blades 13 in engagement with the line. The caps 10, which have been previously slipped over the ends of 85 the line are then threaded on the cylinder, until the inturned flanges 11 abut the ends of the clamp. This connection will then function as an integral part of the clothes line.

If it is desired to substitute another clothes line, one of the caps 10 will be unscrewed, and the respective cylinder 7 pulled off of the respective clamp member and then said clamp member may be removed and the cap 90 also removed from the line. An end of another clothes line will be attached with the parts just removed and by pulling on the free end of the old clothes line, the new clothes line may be trained over the pulley 95 structures C and D, and finally, the other end of the new clothes line may be attached to the connection in the usual manner.

By referring particularly to Figure 4 of the drawing, it will be seen that I have dis- 110

- closed a modification of one of the engaging clamps, which comprises a pair of elongated sides 15 having their extremities turned toward each other to form sheets 16. 5 Extensions 17 are disposed between the sides 15, beginning at their point of juncture and terminating intermediate their ends. Thus, the end of the rope will be received between the sides 15 and the extensions 17.
- 10 It is thought that the construction, operation, and advantages of the invention will now be clearly understood, without a more detailed description thereof.
- 15 It will be apparent that the device is useful in numerous other ways than that outlined above, and that numerous changes in the details of construction, and in the combination and arrangement of parts may be resorted to, without departing from the 20 spirit or scope of the invention as herein-

after claimed, or sacrificing any of its advantages.

Having thus described my invention, what I claim as new is:

A clothes line engaging member including 25 a cylinder having one end closed, and the other end opened, said cylinder provided with external threads adjacent its open ends, a U-shaped resilient clamp receivable in the cylinder, with its intermediate portion adjacent the closed end, the ends of the clamp members being inturned to form blades, and a cap threaded over the open end of the cylinder and provided with an inturned annular flange for engaging the ends of the 30 clamp member to retain it in the cylinder, when said clamp member is engaged with the end of a rope or the like.

In testimony whereof I affix my signature.

SAMUEL J. WALASCHEK.
